UNITED STATES PATENT OFFICE.

LEONARD B. SCHWARCZ, OF NEW YORK, N. Y.

DESIGN FOR A GLOBE FOR A SOAP-DISPENSING DEVICE.

Application filed February 17, 1923. Serial No. 5,192. Term of patent 7 years.

To all whom it may concern:

Be it known that I, LEONARD B. SCHWARCZ, a citizen of the United States, residing at New York, borough of Manhattan, in the county and State of New York, have invented a new, original, and ornamental Design for a Globe for a Soap Dispensing Device, of which the following is a specifica-

tion, reference being had to the accompanying drawing, forming part thereof.

Figure 1 is an elevation of the device.

Figure 2 is a plan view.

I claim:—

The ornamental design for a globe for a soap dispensing device as shown.

LEONARD B. SCHWARCZ.
